CLAIM

The ornamental design for a ball rack, as shown and described.

DESCRIPTION

FIG. 1 is a front perspective view of a ball rack showing my new design.

FIG. 2 is a front elevational view thereof.

FIG. 3 is a rear elevational view thereof.

FIG. 4 is a top plan view thereof.

FIG. 5 is a bottom plan view thereof; and, FIG. 6 is a left-side elevational view thereof, the right-side elevational view being a mirror image.

The broken lines in the figures show portions of the ball rack which form no part of the claimed design.

1 Claim, 6 Drawing Sheets
